UNITED STATES PATENT OFFICE.

H. A. COLLINS, OF SPRINGFIELD, MASSACHUSETTS.

IMPROVED CHECK-HOOK.

Specification forming part of Letters Patent No. 43,834, dated August 16, 1864.

To all whom it may concern:

Be it known that I, H. A. COLLINS, of Springfield, in the county of Hampden and Commonwealth of Massachusetts, have invented a new and Improved Water or Check Hook for Harness-Saddles; and I do hereby declare that the following is a full, clear, and exact description of the construction and operation of the same.

Every person accustomed to the management of a horse understands the use of a water or check hook on a harness-saddle—viz., to form a convenient means of confining the check-rein for the purpose of keeping the head of the horse in a proper position. Now, with the hooks in common use there has been one of two difficulties—they have been so constructed that the process of inserting the rein was very troublesome, or else the rein has been very liable to become unhooked. When a spirited horse is uneasy, it is not a simple matter to get the rein into many of the hooks in common use, owing to the numerous crooks and narrow openings which are made to prevent it from coming out accidentally; also, if these precautions are not taken, the horse will often cause the rein to come out while driving, which is always exceedingly disagreeable, as every person can testify who has been accustomed to drive good horses.

The object of my invention is to make a hook such that the rein can be inserted without twisting, and in such a manner that the motion of the horse's head will cause but little trouble, and at the same time one that will hold the rein securely against any accidental escape and still allow it to be removed by the hand without the least difficulty.

In the drawings, Figure 1 is a perspective view of a harness-saddle provided with my improved hook. Fig. 2 is a section of the same hook; and Fig. 3 is a section of a hook constructed somewhat differently, but accomplishing the same object in substantially the same manner.

I will first describe Figs. 1 and 2. A is the

saddle; B, the hook; C, a spring-tongue attached to the top of the saddle by the bolt *a*, that holds the hook. The top of the spring comes nearly in contact with the back end of the hook, and is curved back a little, so that on bringing the rein back and pressing the edge down between the tongue and hook the spring yields enough to allow the rein to pass into the hook. Now, it will be seen that this operation is performed with the rein in its natural position without any twisting, so that all that is necessary is just to grasp the rein and bring it back onto the hook and drop it directly down, and all is secure. To remove the rein the same process reversed is sufficient—just bring the rein back against the tongue and carry it up in its natural position between the tongue and hook.

While the matter of inserting and removing the rein by the hand is so simple, there is no possibility of an accidental escape, because before the rein can pass out the tongue must be pressed back, and although the motion of the horse's head may throw the rein into almost every possible position, it can have no direct power sufficient to press back the spring.

In Fig. 3, D is the hook proper. E is a tongue hinged to D at *f*. F is a spring inserted in the saddle and pressing against the tongue D, thus keeping it pressed up to or near to the hook and operating in the same manner as the spring-tongue C.

The invention and its operation are both so simple that no further explanation is necessary to enable any one accustomed to driving a horse to see the advantages claimed.

Having thus described my invention, I would state my claim as follows:

In combination with a harness-saddle and check-hook, a spring-lever arranged to close or nearly close the hook, substantially in the manner and for the purposes set forth.

H. A. COLLINS.
